OIL-CUP.

1,331,894.

Specification of Letters Patent. Patented Feb. 24, 1920.

Application filed March 27, 1919. Serial No. 285,592.

To all whom it may concern:

Be it known that I, EDGAR J. BLOOM, a citizen of the United States, residing at Tiffin, county of Seneca, State of Ohio, have 5 invented a new and useful Improvement in Oil-Cups, of which the following is a specification.

This invention relates to oil cups and has for its object an oil cup of such simple construction that it may easily compete with the simplest forms of grease cups even when used in large quantities. The cup only feeds the oil when the part to which it is attached is vibrated and then only in very minute 10 quantities.

The oil cup operates upon the principle of air-sealing the reservoir and utilizing capillary action to avoid the feeding of the oil except where the same is shaken through the 15 orifice or drawn through by the capillary attraction of the oil previously fed through the orifice. The cup is so designed that it is extremely reliable in its feed notwithstanding the great restriction of the flow. Provision is made for the continued presence 20 of the small amount of oil in the capillary orifice to secure reliability of feed. These 25 features of operation can be better explained and amplified when the exact structure is understood.

In the drawings,—

Figure 1 is a side elevation of the cup.

Fig. 2 is a longitudinal section of the cup.

Fig. 3 is a plan view of the barrel of the cup.

Fig. 4 is an inverted plan view of the cap.

Fig. 5 is a longitudinal section of a modified form for use on horizontal bearings.

The cup comprises simply a barrel *a* very similar to any grease cup having an externally screw-threaded nipple *b*, the wrench hold *c* and the screw cap. However, as an 45 integral part of the barrel, there is an inward extension of the nipple *b* to form a stand pipe *e* whose upper end is closed but for a capillary orifice *f* drilled through the end. A basin *g* is turned in the end of the 50 pipe and at its bottom is the orifice *f*.

The cap is internally screw-threaded like any ordinary grease cup cap but the center of the cap has a relatively thick portion which is turned into a shallow cone *i*, whose 55 surface substantially parallels the surface of the basin turned into the end of the stand

pipe. Between the base of the cone and the threads is a flat annulus *h* that acts as a seat for the leather washer *j*. When the cap is turned down upon the end of the 60 barrel, the end of the barrel embeds itself in the washer and makes an absolutely air-tight fit. The stand pipe *e* being an integral part of the barrel absolutely excludes air except as it may find its way through 65 the capillary opening *f*.

When the oil cups on an automobile are to be filled, the caps are taken off, the oil poured into the barrel up to the brim of the barrel, and it is then allowed to run down 70 through the capillary orifice *f* and into the bearing, where it establishes an initial film. With the air pressure behind the oil, the oil will run quite freely through the capillary orifice drop by drop, and the caps can then 75 be screwed down tightly and the feeding of the oil absolutely stopped for two reasons: Ordinarily the level will have fallen below the top of the stand pipe and motion is required to supply new oil to the top of the 80 stand pipe; and secondly for the reason that capillary action is such that even if the oil is up above the stand pipe top, it will not feed unless the cup is in motion. The reason for that is that an absolutely air-tight cup is 85 provided except for the capillary opening. In order for a fluid, with a moderate hydrostatic pressure, to flow through a receptacle with a restricted opening but otherwise air-tight, it is well known that an equal 90 amount of air must be forced up through the liquid by atmospheric pressure to replace the liquid going through the restricted opening. This is the well known action of a bottle. However, if the opening in such a receptacle is very small the adhesion of the fluid to the walls of the orifice (capillary action) is so great that the capillary opening 95 such as I use will suspend a relatively heavy column of liquid by the atmospheric pressure underneath. In short, the opening is so small and the cohesion and adhesion due to the capillary action so strong, that the air will not break through the liquid suspended 100 in the opening and above it and unless it does the liquid will not flow. In fact, actual demonstration shows that a tube, such as I use, having an air-tight relation with the barrel, and the capillary opening (preferably only about 1/70th of an inch) will support a column of water several times the 105 height of the cup and several times the cross

section of the cup if the receptacle is otherwise sealed so air cannot enter.

This principle is utilized in holding up the feed through the capillary opening.

- 5   Absolutely no joints are provided between the stand pipe and the barrel and the joint between the cap and the barrel is packed while the capillary opening is oil-sealed by the constant presence of what might be fig-
 10   uratively called "a pillar" of oil. This pillar of oil results from the peculiar arrangement between the top of the stand pipe and the cone. The cone acts as a collector of a film of oil which is dashed up against the cap. This is shown in Fig. 2. This film runs down the cone and into the basin *g* but it does not drop off from the cone. The proximity of the basin *g* to the head of the cone is such that the oil always adheres to
 15   both the head of the cone and to the basin, keeping a substantially ever-present pillar of oil. This pillar of oil performs at least two very useful functions—it keeps the oil from shaking off the end of the stand pipe
 20   so as to assure regularity of feed, and it also helps to air-seal the capillary orifice, for obviously the pillar of oil presents a greater resistance to air bubbles passing through than would be the case with a mere film of
 25   oil. Perhaps not so much the weight of the oil as the strong cohesion of the oil particles to each other and the strong adhesion to the relatively great area of metal surface provided at this point, achieves this. This
 30   condition is brought about due to the fact that the edge of the cone is only slightly spaced from the surface of the basin and the two surfaces are in substantially parallel position. The spacing in an ordinary cup of
 35   approximately 4/5ths of an inch in diameter is only approximately 8/100ths of an inch. The depression of the basin *g* and the point of the cone dipping down into the pillar of oil tend to securely anchor the oil pillar to
 40   the top of the stand pipe. Obviously with merely a basin in which the oil freely rests, there is considerable more tendency for the oil to slop over and out of the basin, breaking the air-seal and withdrawing the oil so
 45   as to make rather uncertain a reliable feed. This anchorage is such that the jarring motion of an automobile, which will largely vibrate the car in an up and down movement, is not very likely to shake the oil and break
 50   the air-seal. As already explained, this air-seal prevents the rising of bubbles of air, as is ordinarily the case in a bottle, and thereby greatly restricts the flow of the oil through the opening. In fact, it is my ob-
 55   servation that no oil will flow through the opening except when drawn through by capillary attraction due to the oil film in the bearing and the oil contained on the walls of the passage leading to the bearing
 60   65   or else be finally shaken down by the force

of the vibration of the car. This results in very minute feeding of the oil, which is all that is required to properly lubricate the bearing. I have found that an oil cup of this character of ordinary size will not need 70 replenishing for an average of 1500 miles. This results in a system of lubrication that requires very little attention by the operator of the car.

The success of an oil or grease cup in 75 large production to-day depends in a large measure upon the way it can be manufactured. If it involves complicated or expensive operations, it is almost sure to be condemned for large production. I believe it 80 will be evident that the oil cup here shown has a minimum of simplicity for anything that offers an automatic feed. The cup and the cap are preferably castings with the nipple and the stand pipe cast solid. The nipple 85 and the stand pipe may then be drilled for the main bore and the end of the stand pipe turned to provide the basin and the capillary opening drilled. The cone may be turned to make a smooth and regular surface 90 while the various parts of the outside may be turned and the wrench hold finished by use of an emery wheel. The stand pipe and the barrel are one continuous piece, requiring no adjustment or other care. 95

What I claim is:

1. An oil cup, having in combination, a barrel provided with a stand-pipe in air-tight relation therewith, said stand-pipe provided with a capillary orifice in its top, 100 and a cap in air-sealed relation with the barrel, the said inclosure formed by the cap and barrel acting as a reservoir for oil which is restrained from feeding by the inability of the air to get into the reservoir on account of the capillary opening and the air-sealed relation of the other parts of the cup. 105

2. An oil cup, having in combination, a barrel provided with a stand pipe in air-tight relation therewith except for a capillary opening in the top, a cap having an air-sealed relation with the barrel, and a collector suspended above the stand-pipe and barrel for guiding the oil down upon the stand-pipe and in such proximity with 110 the stand pipe as to maintain a pillar of oil thereupon, the said air-tight condition of the reservoir formed by the barrel and cap and the capillary nature of the opening in the top of the stand-pipe serving to exclude 115 air and restrict the flow of the oil. 120

3. An oil cup, having in combination, a barrel provided with a stand-pipe in air-tight relation therewith except for a capillary orifice in its top, a cap in air-sealed relation with the barrel and provided with a cone on its under side having its head coming in such proximity with the top of the stand-pipe as to maintain a pillar of oil 125 thereupon to act as an air-seal, said air- 130

sealed condition of the reservoir formed by the cap and barrel and the capillary nature of the orifice through the top of the stand-pipe and the air-sealing pillar of oil maintained by the cone serving to exclude air from the cup to restrain the feed through the capillary orifice.

4. An oil cup, comprising a barrel provided with a stand-pipe therein having a capillary orifice in its top and a cap maintained in air-sealed relation with the barrel by being provided with a washer interposed between the barrel and the cap whereby air is excluded from the reservoir formed by the cap and the barrel to restrict the flow through the capillary orifice.

5. An oil cup, having in combination, a barrel provided with a stand-pipe in air-tight relation with the barrel except for a capillary orifice in the top, a cap in air-sealed relation with respect to the barrel, and a cone suspended by the cap and having its apex directly above the opening through the stand-pipe to maintain a pillar of oil as an air-seal over the stand-pipe and to anchor such pillar of oil thereto, the said air-sealed relation of the barrel and cap, the capillary opening and the air-sealing pillar of oil maintained upon the top of the stand-pipe serving to exclude air to restrict the feed through the capillary opening.

6. An oil cup, comprising a barrel provided with an integral nipple and an inward continuation of the nipple in the form of an integral stand-pipe having at its top a capillary opening, and a cap maintained in air-sealed relation with the barrel and having its center of increased thickness and formed into a cone adapted to have its apex seat directly above the orifice in the top of the stand-pipe, the reservoir formed by the said barrel and cap being thereby maintained in air-sealed relation to exclude air and restrict the feed through the capillary opening.

7. An oil cup, having in combination, a barrel provided with a stand pipe therein having an air-tight relation with the barrel except for a capillary opening in the top of

the stand-pipe, a basin being provided in the top of the stand-pipe, a cap secured on the end of the barrel in air-sealed relation with respect thereto, and a collecting cone suspended over the top of the stand-pipe and having its apex in close proximity with respect to the basin surface to maintain a pillar of oil and anchor it thereto to form an air-seal for the capillary opening, the said air-sealed condition of the oil reservoir formed by the cap and barrel, the capillary opening and the air-seal maintained by the cone and basin serving to exclude air and to restrict the flow through the capillary opening.

8. An oil cup, having in combination, a barrel, a cap therefor provided on its inside with a pointed cone and a stand pipe rising from the outlet hole in the barrel and provided with a capillary opening drilled therein at the top below the point of the cone, said stand-pipe having also turned therein a basin leading to said capillary opening, the surface of the cone and the surface of the basin being in such proximity with each other that they serve to maintain between the cone and the stand-pipe almost constantly a pillar of oil.

9. An oil cup, having in combination, a barrel provided with an integral nipple and an integral extension of the nipple forming a standing conduit provided with a basin turned in the top of the conduit, a capillary opening drilled into the interior of the conduit through the bottom of the basin, a cap having an annular flange internally screw-threaded and adjacent the threads a washer seat, the central portion of the cap being thickened and turned into the form of a cone, and a washer adapted to seat in the washer seat of the cap and abut the top of the barrel when the cap is screwed onto the external threads of the open end of the barrel.

In witness whereof I have hereunto set my hand on the 8th day of March, 1919.

EDGAR J. BLOOM.
